UNITED STATES PATENT OFFICE

JOSEPH G. HUYE, OF NEW ORLEANS, LOUISIANA

DISPLAY STAND

Application filed October 29, 1928. Serial No. 315,811.

This invention relates to collapsible knock-down set-up display stands such as employed by merchants on their display windows and in their stores and on the tops 5 of their counters to display their goods and is primarily intended for the display of millinery, though equally available to advantage to display a great variety of other articles.

10 The primary objects of the present invention are, to provide a relatively slender high or tall pasteboard display stand with a relatively large area heavy base to give the stand a very low center of gravity and combat its 15 tendency to topple over when goods are being applied to its upper end or removed therefrom; to provide a simple, inexpensive and quick positive means for rigidly securing the pasteboard column to the base; to 20 provide a separate decorative paper cover or fabric cover which may be quickly applied to and removed from the column, whereby said decorative covers may be removed, interchanged or replaced at will as 25 frequently as may be desired, avoiding the unsightly appearance of the cracked corners heretofore present when the decorative paper covering was pasted to the pasteboard prior to the folding or bending of the 30 latter in display stands having columns of angular cross-section; to provide a very firm long slender stand which may be shipped flat and quickly assembled, or quickly taken apart and the column thereof collapsed preparatory to storage for conservation of storage space; to provide a very graceful and attractive display stand of small shipping weight and bulk and extremely economical to manufacture, both as to materials and as 40 to manufacturing and assembling operations; and to improve the detail features of such display stands, all as hereinafter more particularly set forth, described and claimed.

In this application I show but several of 45 the preferred embodiments of my invention simply to illustrate the practice of my said invention as by law required. However, I realize that my invention is capable of other and different embodiments and that the various details thereof may be modified in vari-

ous ways, all without departing from my said invention. Therefore, the drawing and description herein are to be considered as merely illustrative and not as exclusive.

Heretofore it has been the practice to 55 make tall display stands of wood or metal in order to obtain the necessary weight and base. However, not infrequently one of these, unless it has an extremely wide base, will be upset or topple over during the removal of a hat from it, as the natural movement in removing a hat when waiting on a customer is partly horizontal as well as vertical, thus shoving the top of the display stand sidewise so that the wooden column or 60 stem is inclined and the weight of the upper part thereof exerts a leverage on the base under the influence of gravity. Further such wooden stands must be of a good grade of wood with a costly finish and make a 65 rather expensive display article and, because of their tendency to topple over, are frequently marred so that their upkeep is a decidedly appreciable item to the merchant who takes a pride in the appearance of his 70 displays.

It has been usual heretofore to employ pasteboard display stands on top of counters and on stands in display windows, but such pasteboard display stands are relatively 75 short, usually rest on the rims of the vertical tube, and must have a very wide base to give the necessary supporting base and are very easily damaged because unbraced and unprotected at their lower portion.

In the accompanying drawings:

Figure 1 represents a perspective view of a device embodying my invention as employed to display a ladies' hat in a display window;

Figure 2, a side elevation thereof, with the lower end in central vertical cross-section, the connecting bolt and nut being shown in elevation;

Figure 3, a sectional view on the line 3—3 95 of Fig. 2 of the column or tubular post 1 by itself, looking in the direction of the arrows;

Figure 4, a view on line 4—4 of Fig. 2, looking in the direction of the arrows;

Figure 5, a sectional view on a line corresponding to line 3—3 of Figure 2, of the stand as assembled and erected as illustrated in Figure 2;

5 Figure 6, a perspective separated view of the parts; and

Figure 7, a fragmentary detail sectional view of a slight modification wherein the decorative paper covering *b*' is not clamped 10 with the end tongues 7 between the wooden blocks 3 and 5.

Referring now in detail to the drawing, 1 designates the long slender pasteboard tubular column or body of the stand, preferably angular in cross-section, having 15 tongues 7 preferably integral with its lower end and each folded in the same horizontal plane on a straight line and fitting between a preferably relatively thin wooden clamping block 5 fitting in the lower end of the 20 column 1, and a thicker and much larger base block 3, said blocks 5 and 3 being drawn and held together against said intervening tongues 7 by a slotted head bolt 6 25 extending through the center of said block 5 and the center of said block 3 and into a recess 4 in the bottom of said block 3 and receiving on its screw-threaded lower end portion protruding into said recess a wing 30 nut 10, said nut serving to draw the screw or bolt 6 up tight to clamp the parts tightly together to prevent any relative endwise or turning movement between them, and to facilitate the screwing of the nut 10 on the bolt 6 a narrow staple having a bar portion 35 not exceeding in cross-section or with the width of the slot in the head of the bolt 6 is driven into the upper face of the block 5 in such location that its bar portion will lie 40 in said slot of the screw 6, so holding the screw or bolt 6 against turning and also preventing its endwise displacement with relation to the block 5. Preferably the bolt 6 will be of the bevel head slotted type and 45 the upper face of the block 5 will be countersunk to receive said head of the screw so that the upper face of said head will lie flush with the top of the block 5 as shown. However, this is a decidedly minor feature, 50 any other suitable type of bolt may be employed, and it is not essential that it shall be slotted or that the staple 8 be employed, though it is important that, whatever the type of bolt employed, and whatever the means employed, as assembled or associated prior to the assembly or erection of the stand, the block 5 and the screw 6 shall be 55 substantially relatively immovable in an axial direction and also in a direction peripheral of said screw, though it is not objectionable if the screw should have a little play or wobbling movement relative to the block 5.

The block 5 will preferably be of the same shape as the lower end of the column or

body 1 and of such size as to make a nice fit in the lower end thereof, as illustrated in Figures 2 and 4, and the block 3 will preferably be of the same shape, but preferably twice the dimensions thereof, or more, to give a wide supporting base to the stand, and the exposed base block 3 may be covered with a decorative covering paper *c*, shown of exaggerated thickness in Figs. 2 and 6. The dimensions, weight and thickness of the blocks 3 and 5 will preferably be determined 70 in a general way with relation to the size of the particular display stand, the said blocks 3 and 5 together with the bolt 6 and nut 10 weighing preferably at least twice as 75 much as the column 1 with its tongues 7, so that even though the display stand as a whole be rocked way over much farther than usual in removing a hat, the rocking contact with the floor will be along one edge or at 80 one corner and the rest of the block 3 being disposed to one side of said point and exerting its weight as a lever will force the stand to quickly right itself, the leverage exerted by said blocks 3 and 5 and their weight being in excess of the weight plus the leverage 85 of the stand or column 1.

The recess 4 will of course be of such depth as to entirely receive the wing nut 10, and the bolt 6 will of course be of less length than the combined thicknesses of the blocks 3 and 5 and the interposed tongues 7 so that 90 it will not extend beyond the lower face of the block 3 so that said block will rest perfectly flat and even on the floor or top of a 95 counter.

In order to provide for frequent change 100 in the finish of the column 1 and to avoid the cracking of the decorative paper covering at the corners, as occurs when the covering is pasted to the surface of an angular body subject to folding at said corners, the column 1 will preferably be formed of a pasteboard body *a* formed of a single piece formed into tubular shape and pasted together or otherwise suitably secured together in usual manner by the usual overlap, as illustrated in Figs. 3 and 5; and a decorative tubular sleeve 105 flexible preferably decorative paper covering *b* conforming in shape to the external face of the body *a* and of such size as to make a snug glove fit thereon, and will have tongues of the same size as, and conforming in position to, tongues 7, so as to fit with the latter between the blocks 3 and 5 and be clamped 110 thereby, whereby said blocks will serve to secure said decorative covering *b* in place.

To assemble, the block 5 will be inserted 115 in the lower end of column 1 and the tongues 7 will be folded over against said block 5, when the block 3 will be applied to the end of bolt 6 and moved up against the tongues 7, the nut 10 then being screwed on the end of bolt 6.

In the modification illustrated in Figure 7 120

the construction and operation are in all respects the same as above described, except that the decorative tubular covering *b'* does not have the tongues fitting between the blocks 3 and 5, but instead is held in position on the column 1 by means of a decorative elastic band 9 fitting around the extreme lower end portion of said covering *b'* and holding it against the outer face of the lower end portion of column 1, and in this form to remove said covering *b'* and replace it with a fresh covering *b'* it suffices merely to remove the elastic band 9, remove the decorative covering *b'*, replace it by a new decorative covering *b'* and then replace the elastic band 9 in proper position.

While I have shown and described the stand as angular in cross-section, it need not be quadrilateral as shown, but may be of any angular or other cross-sectional shape desired, any suitable means, other than that shown, for drawing and securing the blocks 3 and 5 together may be employed if preferred, and any suitable materials, other than those mentioned, may be used for the various elements, or any of them if preferred.

Having thus described my invention, what I claim as new and desire to secure by United States Letters Patent is:

3. A display stand comprising a light tubular vertical member having tongues connected to its lower end portion and adapted to be folded inward, in combination with a small block disposed in the lower portion of said tubular member immediately above said tongues as folded, a flat bottomed block of much larger transverse area than the base of said tubular member, and means for drawing and holding said blocks toward each other into clamping engagement with said tongues interposed between said blocks.

2. A display stand comprising a light tubular vertical member having tongues connected to its lower end portion and adapted to be folded inward, in combination with a small block disposed in the lower portion of said tubular member immediately above said tongues as folded, a flat bottomed block of much larger transverse area than the base of said tubular member, and means for drawing and holding said blocks toward each other into clamping engagement with said tongues interposed between said blocks, the total weight of said blocks and means being in excess of the weight of said tubular member.

3. A display stand comprising a light tubular vertical member having tongues connected to its lower end portion and adapted to be folded inward, in combination with a small block disposed in the lower portion of said tubular member immediately above said tongues as folded, a flat bottomed block of much larger transverse area than the base of said tubular member, and means for drawing and holding said blocks toward

each other into clamping engagement with said tongues interposed between said blocks, the total weight of said blocks and means being at least twice the weight of said tubular member.

4. A display stand comprising a tubular pasteboard vertical member having integral tongues extending from its lower end portion and foldable on the line of the bottom edge of said member inward into a horizontal plane, in combination with a small block disposed in the lower portion of said tubular member immediately above said tongues as folded, a flat bottomed block of much larger transverse area than the base of said tubular member, and means for drawing and holding said blocks toward each other into clamping engagement with said tongues interposed between said blocks.

5. A display stand comprising a light tubular vertical member having tongues connected to its lower end portion and adapted to be folded inward, in combination with a small block adapted to be disposed in the lower portion of said tubular member immediately above said tongues as folded, a flat bottomed block of much larger transverse area than the base of said tubular member adapted to be disposed immediately below said tongues as folded, with its center vertically in alignment with the center of said small block, a bolt extending vertically through the center of said small block, means for holding said bolt against axial and rotary movement relative to said small block, said large block being centrally vertically bored to receive said bolt and recessed in its lower face above said bore, and a nut received in said recess and turning on the lower end portion of said bolt, to draw said blocks together to clamp on the said tongues interposed between them, said bolt being of less length than the combined thickness of said blocks and the interposed tongues, and said recess being of such depths as to completely receive said nut.

6. A display stand comprising a pasteboard tubular member having tongues connected with its lower end portion and foldable on the line of the lower edge of said member inward into a horizontal plane, and a decorative flexible tubular covering of the same shape as said member and of such size as to make a snug fit thereon, said decorative covering having tongues extending from its lower end portion and of the same size, shape and location as said body tongues and respectively lying against the respective bottom faces thereof as folded, in combination with a small block adapted to be disposed in the lower portion of said tubular member immediately above said tongues as folded, a flat-bottomed block of much larger area than the base of said tubular member and adapted to be disposed immediately below

said tongues as folded, and means for drawing and holding said blocks toward each other to clamp between them the superposed interposed tongues of said tubular member and said cover.

In testimony whereof, I have signed my name to this specification at New Orleans, Louisiana, this 22 day of October, 1928.

JOSEPH G. HUYE.
